UNITED STATES PATENT OFFICE.

JAMES R. STULL, OF LOS ANGELES, CALIFORNIA.

WHEEL DRESSER.

Application filed February 13, 1922. Serial No. 536,290.

To all whom it may concern:

Be it known that I, JAMES R. STULL, a citizen of the United States, residing at Los Angeles, in the county of Los Angeles, State 5 of California, have invented certain new and useful Improvements in Wheel Dressers, of which the following is a specification.

This invention has to do with a device for dressing wheels, such as emery wheels, 10 and the like, and it is an object of the invention to provide a simple, convenient, effective device of this character.

Grinding wheels are extensively used in finishing parts or articles and in many instances 15 are used in forming parts or articles. These wheels must be kept round and their faces must be kept properly dressed otherwise they become inefficient or inoperative.

20 A feature of this invention is the provision of a simple, effective device which can be used to quickly and effectively dress a grinding wheel. The device is extremely simple of construction and operation and 25 therefore is valuable commercially and is practical to use.

The various objects and features of the invention will be best and more fully understood from the following detailed description 30 of a typical preferred form of the invention throughout which reference is had to the accompanying drawings in which—

Fig. 1 is a fragmentary perspective view of a typical grinding wheel showing the device 35 provided by the present invention in place to dress the face of the wheel; Fig. 2 is a longitudinal detailed sectional view of the device provided by the invention; and Fig. 3 is a side elevation of the device being a view taken as indicated by line 3—3 on Fig. 2.

The device provided by the present invention comprises, generally, a socket 10, a cutting member 11 carried by the socket 10, 40 and a handle 12. In the preferred form of the invention the handle 12 is a hollow rod or tube sufficiently long to allow the operator to conveniently grip it and to obtain the necessary purchase. The socket 10 is a cup like socket formed in the outer end of a tip 45 13 which is detachably carried at the outer end of the handle 12. The tip 13 is preferably formed of a hard durable metal such as tool steel, or the like, and is comparatively small so that it can be manufactured 50 at a reasonably low cost. In the preferred

form of the invention the tip 13 is connected to the outer end of the handle 12 by a screw thread connection for instance, the inner end of the tip 13 is formed with a 50 projection or lug 14 which screw threads into the outer end of the handle 12. The tip 13 is formed at opposite sides with flat parts 16 which can be gripped or engaged by a wrench, or the like, when it is desired 55 to detach it from the handle.

The socket 10 is a round cup like socket sufficiently large to freely carry the cutting member 11. In practice the exact size, 60 depth, shape, etc., of the socket 10 will, of course, depend upon the shape, or characteristics, of the cutting member. When the cutting member 11 is round or spherical it is preferred that the socket 10 be cup shaped so that it conforms more or less to the curvature 65 of the cutting member and that it be sufficiently deep to receive approximately half of the cutting member.

The cutting member 11 is carried in the socket 10 so that it can rotate and is preferably spherical so that it will readily rotate in any direction. It is particularly convenient to obtain spherical members which will effectively serve as cutting members. In practice I have found that ordinary 70 steel ball-bearings, which are, of course, very easily obtainable, form particularly suitable cutting members 11. It also may be pointed out that it is particularly easy to obtain ball-bearings of various sizes and therefore to obtain cutting members which will properly and most effectively be carried in the socket 10 as the socket wears. For instance, when the socket is first formed or is new it may be of a size to effectively 75 carry a medium sized ball-bearing while after the device has been used for some little time the socket may have worn to be sufficiently large to receive and properly carry comparatively a large ball-bearing.

In accordance with the invention the handle 12 is used as a carrier for extra cutting members and for cutting members of various sizes. A projection 20 extends inwardly in the handle near its outer end to prevent the cutting members carried in the handle from becoming displaced from the handle through the outer end of the handle when the tip 13 is removed, and a top or plug 21 is screw threaded into the inner 80 end of the handle to prevent the cutting member carried in the handle from being 85 90 95 100 105 110

displaced from the handle through the inner end of the handle. It will be obvious, of course, that the plug 21 can be detached from the inner end of the handle whenever it is desired to place cutting members in or remove cutting members from the handle.

In Fig. 1 of the drawings I have illustrated a typical grinding wheel 25 for the purpose of illustrating a typical manner 10 in which the device of the present invention may be applied to a wheel for the purpose of dressing it. The grinding wheel 25 comprises a wheel 27 carried on a spindle 28 which is supported in bearings 29 carried by frame parts 26. A rest 30 is carried by the frame parts 26 near the periphery or face of the wheel in the usual manner. To dress the wheel 27 with the device provided by the present invention a 20 suitable cutting member 11 is arranged in the socket of the device and the tip 13, or outer end portion of the handle 12, is arranged on the rest 30 so that the cutting member is in engagement with the face of 25 the wheel. The handle 12 of the device is firmly gripped and held by the operator so that the cutting member is in pressure engagement with the wheel 27. The wheel is rotated and the operator manipulates the 30 device, through the handle 12, to bring the cutting member into engagement with those parts of the wheel that are to be cut away. Upon causing the cutting member 11 to bear against the face of the wheel 35 with a little pressure the material of the wheel is quickly cut away. By properly manipulating the device the face of the wheel 27 can be truly squared off or it can be dressed to have any desired configuration. In practice I have found that the cutting member 11, when in the form of a steel ball bearing carried in a socket formed in a tool steel tip, will quickly and effec-

tively dress a grinding wheel upon being held in pressure engagement with it. Further a device made in accordance with this invention leaves the grinding wheel sharp after it has been dressed. If the socket 10 wears too large or wears out of shape it can be easily and quickly repaired by removing the tip from the handle and placing it in a lathe, whereupon a new socket can be very easily and quickly cut in its outer end.

Having described only a preferred form 55 of my invention I do not wish to limit myself to the particular details hereinabove set forth but wish to reserve to myself any changes or variations that may appear to those skilled in the art or that may fall 60 within the scope of the following claims.

Having described a preferred form of my invention, I claim:

1. A device for dressing a wheel comprising a handle, a cup shaped socket carried by the handle, and a spherical cutting member rotatably carried in the socket.

2. A device for dressing a wheel comprising, a hollow open ended handle, a plug screw threaded into one end of the handle, 70 a hard metal tip screw threaded into the other end of the handle, a projection extending into the handle near said last mentioned end thereof, a cup shaped socket in the tip, and a hard metal ball rotatably carried in the socket with a part projecting from the socket.

3. A wheel dressing device, embodying a handle having at one end a cup shaped socket, and a hardened ball freely rotatable 80 in all directions in the socket and projecting beyond the end of the handle.

In witness that I claim the foregoing I have hereunto subscribed my name this 17th day of November, 1921.

JAMES R. STULL.
